METHOD OF MANUFACTURING BRUSHES

Franz Neuschaefer, Rye, N. Y.; Helen Neuschaefer, executrix of Franz Neuschaefer, deceased, assignor to Helen Neuschaefer, Rye, N. Y.

Original application February 19, 1942, Serial No. 431,473. Divided and this application October 26, 1942, Serial No. 463,342

6 Claims. (Cl. 300—21)

This invention relates to brushes, and methods for manufacturing same.

This application comprises a division of my copending application Ser. No. 431,473, filed February 19, 1942.

Various types of liquid, such as for cosmetic purposes, paints, adhesives, oils, etc., are marketed in small bottles provided with caps or stoppers in which a small brush is mounted to suspend into the bottle, for applying the liquid to surfaces upon which it is to be used. Such brushes heretofore have generally comprised a tuft of hair or other bristle material embraced by a stem portion in the form of a so-called Japanese quill, or in the case of such brushes of domestic manufacture, a stem comprising a single piece of sheet metal rolled or curled into a tubular shape. The present invention provides methods and means for economically manufacturing in large quantities, brushes for like purposes, as well as larger forms and other types of brushes, without using such quills and preferably without requiring the use of metal for the stems.

With preferred examples of the present invention, the stems for a large plurality of the brushes may be simultaneously formed with the brush tufts secured therein, by making use of strips or layers of cardboard or the like materials such as heavy paper, plastic material, thin wood or other sheet material, which may be die-stamped in connection with properly arranged groups of the tufts, so as to simultaneously form comparatively large groups of separate or easily separable brushes with the stems affixed thereon.

Various further and more specific objects, features and advantages of the invention will appear from the detailed description given below taken in connection with the accompanying drawings forming a part of this specification and illustrating by way of example various preferred embodiments of the invention. The invention consists in such novel features, arrangements, combinations of parts and method steps as are described in connection with the embodiments of the invention herein disclosed by way of example only.

In the drawings, Figs. 1 and 2 are side elevational views of die members in open and closed positions respectively, as arranged for shaping the strips or layers of stem-forming material with corrugations preparatory for application thereto of the brush tufts;

Fig. 3 is a view showing the lowermost of the die members of Figs. 1 and 2, with one of said

layers resting thereon after being formed with corrugations and with a plurality of brush tufts placed in such corrugations respectively;

Fig. 4 shows the die members, layers and tufts in position for pressing the brush parts together and for separating the material of each brush stem from the material of adjacent stems;

Fig. 5 is a plan view showing the lower die member with a plurality of finished brushes resting thereon;

Fig. 6 is a detailed sectional view illustrating an alternative method of practicing the invention;

Fig. 7 is a perspective view illustrating two groups of the finished brushes in separate or separable condition;

Figs. 8 and 9 are transverse and longitudinal sectional views showing mold assemblies similar to that of Fig. 4, but with provision for heating the molds. This may be desirable for drying or hardening an adhesive for securing the layers of stem material to the tufts, or for suitably processing the layers or strips of stem-forming material when same comprise a thermo-plastic substance; and

Fig. 10 is a view similar to Fig. 5, but showing an alternative embodiment of the invention.

Referring now to Figs. 1-5 in further detail, a first or lower die member is indicated at 10, a second or layer pre-forming die member at 11, and a third die member at 12. The die members may be provided or formed with suitable pins as at 13 and apertures as at 14, for securing proper alignment in a conventional way.

The lower die member may be formed with two elongated somewhat raised areas as at 15, 16 which are spaced apart by a substantial distance such as indicated at a (Fig. 5) for a purpose hereinafter explained. Each of these raised areas may be formed with transversely extending parallel or substantially parallel corrugations or scallops 17, the corrugations at one area as shown being preferably in alignment with corresponding corrugations on the other raised area. And such corrugations should preferably have a cross section approximately the same in size and shape as one-half of the cross section of the desired finished brush stem with the brush tuft secured therein.

The third or top die member 12 may be the same or substantially similar to the die member 10, and with corrugations or scallops as at 17' complementary to those on the die member 10.

The second die member 11 may be formed on its lower and upper surfaces with a series of

ridges as at 18, 18', adapted to substantially fit within the corrugations 17, 17' respectively. As above indicated, the stem-forming material may comprise strips or layers of cardboard, heavy paper, thin wood, plastic or other sheet material. In carrying out the preferred embodiment of the method, a layer or strip of such material as at 20 is placed upon each of the corrugated areas 15 and 16 of the die member 10. The die member 11 is then placed in position on these strips and a similar pair of strips as at 21 may be interposed between the upper surface of die member 11 and the lower raised corrugated surface areas of die member 12, as shown in Fig. 1. The die members may then be pressed together as in Fig. 2 whereby the layers 20, 21 are shaped with corrugations as shown. The pressure applied at this stage is preferably insufficient to cause the ridges or raised areas as at 22 between corrugations to cut or sever the strips 20, 21. That is, the primary object of the operation illustrated in Fig. 2 is to simply form depressions or corrugations in the layers 20, 21 so that brush tufts as at 23 may be readily positioned in proper parallel relationship in the corrugations thus formed as shown in Fig. 3. Hence, either the pressure as applied in the step of Fig. 2 should be insufficient to cut or sever the strips 20, 21 into separate stem portions or else care should be taken that the ridges 22 between corrugations are not so sharp as to cause such severing, until greater pressure is applied at a later stage in the process.

After the layers or strips 20, 21 have been corrugated in the manner shown in Fig. 2, the two upper die members may be removed and the brush tufts 23 respectively may be placed in position in the corrugations of strip 20 as shown in Fig. 3. The tufts used are preferably long enough to be ultimately cut into lengths for providing at least two brushes. One end of each such tuft may be placed in position to rest within a corrugation on a strip 20, which in turn rests on raised area 15 of one side of the die member 10, and the other end of the tuft may be placed in a corrugation of another strip 20 resting on the other raised corrugated area 16 at the other side of the die member, as will be apparent from Fig. 5.

In case the layers 20, 21 are formed of fibrous or other sheet material which is not in itself of an adhesive character, then the ends of the brush tufts before being positioned as in Fig. 3 may be dipped in a suitable adhesive, or adhesive may be applied to the surfaces of the strips 20, 21 which are to contact the tufts. If desired, the layers 20, 21 may be impregnated as well as coated with a suitable adhesive or thermo-plastic material. In the event the layers 20, 21 are formed of plastic or thermo-plastic material, additional adhesive means may be unnecessary.

After the tufts are in position as in Fig. 3, the upper layers or strips 21 may be placed thereon and the upper die member 12 then placed and pressed in position as shown in Fig. 4, sufficient pressure being applied to squeeze the ends of the brush tufts into compact condition and to cause the corrugated portions or strips 20, 21 to firmly embrace and adhere to the tufts. At the same time if desired, such pressure may be utilized to cause the more or less sharp areas 22 between the mold corrugations to partially or wholly sever the strips 20, 21 along lines between each brush tuft, to thereby separate the material into distinct stem portions of the desired shape. However, in some cases, depending upon

the character of the material used for the strips 20 and 21, it may be desirable to merely scar the material along lines between the brush stems, so that each individual brush later may be easily broken or cut away manually or automatically. That is, in some cases it may be desired to provide automatic machinery for assembling the finished brushes in connection with bottle caps or handles. In that case, the brushes as they leave the above described dies may be in the form of two attached groups, whereby the individual brushes may be severed from the remainder of the group in the automatic assembling machine.

Either before or after the brushes have been removed from the dies, the tufts may be severed along lines such as at 24 (Fig. 5) for example mid-way between the two corrugated raised areas 15 and 16, viz. mid-way between the stem portions which have been formed on the respective ends of each tuft. Thus each tuft serves to provide active brush-forming portions as at 23, 23' for two separate brushes. The length of these active portions of the brushes may of course be determined and varied as desired by varying the spacing *a* (Fig. 5) between the two raised corrugated areas 15, 16. Similarly the lengths of the stem portions may be varied by varying the width of said raised corrugated areas.

In some cases it may be found desirable to use strips such as 20, 21 which have previously been suitably corrugated by known methods, and such strips may be fitted into the die members 10, 12 as in Fig. 4, so that die member 11 and the operations of Figs. 1 and 2, will be unnecessary. In other cases it may be found possible to readily place or distribute the tufts, hair or bristles upon the lower strip 20 while it is still in flat condition and then place a flat strip 21 upon such bristles so placed, and to then apply the die member 12 as in Fig. 4. Such procedure will be further described hereinafter in connection with Fig. 6.

In other cases it may be found desirable to use stem-forming material in the form of a powdered or paste plastic. In that event strips or bands of such plastic may be positioned above and below the tufts in substantially the same way as indicated at 20, 21 (Figs. 3 and 4). That is, as more specifically shown in Fig. 8, plastic or plaster material as at 25 may be distributed over the corrugated surfaces of a lower mold member 10', the brush tufts 23 then being placed in position, whereupon the upper surfaces of the tufts are also then covered with plastic or plaster material 25 at the areas which will contact the upper mold member 12'. As indicated, the mold members 10', 12' may be heated in a suitable well-known way to afford the desired treatment of the plastic material under heat and pressure. A cross-sectional view taken lengthwise of the brushes, of a similar mold is indicated at Fig. 9. In some cases it may be desirable to provide the material 25 in the form of solid strips of relatively soft and deformable plastic which will harden upon application of the heat and pressure.

Fig. 7 illustrates two groups of the finished brushes as made with the dies or molds of Figs. 1-5. It will be noted that each brush comprises a tuft 23 and a stem comprising two semi-cylindrical portions 26, 27 of cardboard or the like, adhesively secured together along their longitudinal edges and embracing the end of the tuft, and thus adhesively and substantially integrally secured thereto. Although these semi-cylindrical

drical portions as made according to the method of this invention may, if desired, be formed of thin sheet metal adhesively secured in place, ordinarily a less expensive construction will be provided if cardboard or other inexpensive fibrous or plastic sheet material is used.

For some purposes the brushes need not necessarily comprise tufts of cylindrical shapes and it will be understood that the corrugations on the dies may be formed with various cross-sectional shapes depending upon the cross-sectional shape of the desired brush tuft or its stem. For example, in many cases the tufts may be substantially flat in cross section and in this event the invention may be practised in a manner indicated in Fig. 6 without arranging the bristles in separate tufts. Instead, the bristles of hair or other material may be combed straight and interposed as a layer 30 between a pair of layers or strips 31, 32 of the desired stem-forming material, including adhesive or to which adhesive has been applied. Then this assembly of material may be subjected to pressure with heat if desired, between lower and upper die members as at 33, 34. These die members will act in generally the same manner as with above described embodiment of Fig. 4 and will serve to separate not only the stem-forming material to the extent desired into distinct stems, but also serve to separate the layer of bristles into separate tufts within each stem as formed.

In some cases, particularly where the bristles or tufts may be formed of long strands of artificial fiber, it may be desirable for quantity production to provide tufts of a length sufficient so that they may be cut into more than two separate brushes. In that event, the tufts may be of a length such as indicated in Fig. 10 so as to extend and protrude out beyond both edges of each of the corrugated raised die areas 15, 16. In this case each completed brush stem portion as formed may be cut into two, as along lines 35, 36, as well as cutting the tufts along line 24. Thus each tuft as used will eventually provide four separate brushes. It will further be understood that the dies or molds may be each formed with more than two corrugated areas, making it possible to originally form more than two stem portions on each tuft and enabling the tuft and its several stem portions to be severed for forming more than four groups of brushes.

The term "bristles" as used in the appended claims is intended to refer to hair as well as other natural or artificial fibers which may be used for brushes. The term "strip or layer" as used in the appended claims is intended to apply, except where otherwise specified, to material which may be solid, semi-solid, or in paste or powdered form.

While the invention has been described in detail with respect to particular preferred examples, it will be understood by those skilled in the art after understanding the invention, that various changes and further modifications may be made without departing from the spirit and scope of the invention, and it is intended therefore in the appended claims to cover all such changes and modifications.

What is claimed as new and desired to be secured by Letters Patent is:

1. Method for forming simultaneously a plurality of brushes, which comprises arranging a series of tufts in generally parallel relationship, applying and adhesively securing thereto, two strips of deformable material extending transversely of the tufts and spaced apart by a substantial distance, also deforming said strips into a plurality of distinct stem portions each extending along and substantially embracing a tuft, and severing said tufts at points between said strips, thereby forming two groups of brushes.
- 15 2. Method for forming simultaneously a plurality of brushes, which comprises interposing and adhesively securing a series of tufts in generally parallel arrangement between pairs of superposed strips of cardboard or the like, extending transversely of the tufts, with one pair spaced substantially from another, also die-forming said strips of each pair conjointly into a plurality of distinct stem portions, each embracing a tuft, and severing said tufts at points between said pairs of strips, thereby forming groups of brushes.
- 20 3. Method for forming simultaneously a plurality of brushes, which comprises arranging a series of tufts in generally parallel relationship, applying thereto a strip of thermo-plastic material extending generally transverse to the tufts, and shaping said material under heat and pressure sufficient to deform same into a plurality of substantially distinct stem portions and sufficient to also cause the thermo-plastic material of said portions to adhesively embrace said tufts respectively.
- 25 4. Method for forming simultaneously a plurality of brushes, which comprises arranging a series of bristles in generally parallel relationship in contact with a transversely extending strip of thermo-plastic material, and shaping said material under heat and pressure sufficient to deform same into a plurality of substantially distinct stem portions, and sufficient to also cause the thermo-plastic material of each of said portions to adhesively embrace a tuft of the bristles.
- 30 5. Method for forming simultaneously a plurality of brushes, which comprises arranging a series of bristles in generally parallel relationship in contact with at least two substantially spaced-apart thermo-plastic strips which extend transversely of the bristles, shaping said strips under heat and pressure sufficient to deform same into a plurality of distinct stems, and sufficient to also cause the thermo-plastic material of each of said portions to adhesively embrace a tuft of bristles, and severing the tufts at points between said strips, thereby forming groups of brushes.
- 35 6. Method for simultaneously forming a plurality of brushes comprising, corrugating transversely a strip of deformable material, placing ends of brush tufts in said corrugations, and covering said ends with, and adhesively securing thereto and to said first strip, another similarly corrugated strip, so applied under pressure as to at least partially separate the strips into brush stems, along lines of the corrugations.

FRANZ NEUSCHAEFER.
